H. A. DEEKS

GASOLINE FILTER

Filed April 14, 1922

Inventor,
H.A. DEEKS.

By Fetherstonhaugh & Co.
Atty.

UNITED STATES PATENT OFFICE.

HUGH ALLEN DEEKES, OF TORONTO, ONTARIO, CANADA.

GASOLINE FILTER.

Application filed April 14, 1922. Serial No. 552,543.

To all whom it may concern:

Be it known that I, HUGH ALLEN DEEKES, a subject of the King of Great Britain, and a resident of the city of Toronto, in the county of York, Province of Ontario, Canada, have invented certain new and useful Improvements in Gasoline Filters, of which the following is the specification.

My invention relates to improvements in gasoline filters pertaining more particularly to filters applicable to use between the gasoline tank and the carburetor of a motor vehicle and acting as a purifying device for the gasoline to enable the carburetor to be supplied with clean fuel.

A further object is to devise means whereby upon the gasoline in the filter casing reaching a predetermined level it will be permitted to flow through the outlet without passing through the filtering medium which is impervious to water.

A still further object is to devise means for holding the different removable portions of the filtering unit in their co-related positions in the casing.

My invention consists of a gasoline filter constructed and arranged all as hereinafter more particularly described and illustrated in the accompanying drawing in which:

Fig. 1 represents a side elevation of a filter constructed according to my invention showing the means for mounting it on the vehicle.

Fig. 2 is an enlarged vertical section through the filter showing the filtering unit in section therein.

Fig. 3 is a front elevation of the filter casing with the casing closure and the adjusting collar removed to expose the filtering medium impervious to water which is broken away to expose the screen of the by-pass and the main filtering screen, and

Fig. 4 is a perspective view of the adjusting collar.

Like characters of reference indicate corresponding parts in the different views.

1 is the casing which is constructed with one end wall of substantially semi-elliptical shape and the other end open and provided with an outwardly extending peripheral flange 2 outwardly inclined to the vertical from top to bottom.

3 is a gasoline inlet from the gasoline storage tank suitably positioned in the casing as is illustrated in Fig. 2, such casing being

indented so that the longitudinal axis of the inlet nipple will lie substantially horizontal.

4 is a drain plug in the bottom of the casing adapted to be screwed into the boss 5 which is provided with suitably extending orifices 6 in order that any dirt or deposit from the gasoline falling to the bottom of the casing will be expelled therefrom upon the plug 4 being removed. 7 is a shoulder constituted in the casing, the plane of the shoulder being substantially parallel to the flange 2.

8 is a metal gauze screen partition extending across the casing 1 and seated on the shoulder 7. 9 is a chamois-carrying ring provided with an outwardly extending bead 10 at its outer end and with an outwardly extending flange 11, at its inner end, said flange engaging the screen 8 and seating it firmly on the shoulder 7 upon the ring being placed in position.

12 is a chamois extending over the beaded end 10 of the ring 9 and 13 is a double metal gauze screen of U-shaped cross section extending over the by-pass orifice 14 in the top of the ring 9.

15 is an annular chamois supporting ring seating collar provided with a convexed outer end with an orifice therein, said collar engaging the outer side of the flange 11 of the ring 9 and its convexed end engaging the casing closure 16 which is provided with a peripheral flange 17 adapted to be applied to the aforesaid casing flange 2, a suitable washer being interposed between the two flanges to seal the same. The closure is held in engagement with the casing by means of the cap screws 19 being threaded through the flanges 17 and 2 respectively. 20 is a centrally located gasoline outlet in the closure 16.

21 is a bracket secured to the flange 2 and adapted to support the filter casing on the vehicle in the position illustrated in Figs. 1 and 2.

22 is an inwardly extending rib formed in the top of the casing 1 between the shoulder 7 and its outlet end, said rib adapted to engage a notch 23 in the top of the flange 11 of the ring 9 for preventing the ring turning out of its correct position in which the by-pass 14 is situated at the top thereof.

My device operates as follows:—

When the gasoline is fed in through the inlet 3 into the casing 1 any dirt or the

like will be caught by the screen 8 and deposited in the casing 1 and drained off by removing the plug 4. It is to be noted that owing to the inclination of the screen 5 particles of dirt and other foreign matter will not have a tendency to cling to the meshes of the screen but will tend to drop off. Any water in the gasoline will be prevented from reaching the outlet owing to 10 the chamois screen 12 and can likewise be drained from the casing by removing the plug 4.

It is found that when chamois is new and for the first couple of months of its 15 use that it has a tendency to prevent the free flowing of the gas therethrough to the outlet 20 and such difficulty is overcome by providing the by-pass 14 which will permit the gasoline after passing through the 20 screen 8 to pass through the double screen 13, through the by-pass 14 to the outside of the ring and outwardly between the outside of the ring and the inside of the adjusting collar 15 to the outlet 20. This is 25 of course only possible when the gasoline in the casing has reached a sufficient height but this height is soon reached when the chamois diaphragm 12 is blocked, and the gasoline fills the inlet side of the casing. 30 This by-pass would also be of advantage where gasoline with an excess of water is used and then such water would have a tendency to block the pores of the chamois and prevent the gasoline flowing freely 35 therethrough to the outlet.

The chamois supporting ring seating collar 15 is provided with the orifice 16 therein so that owing to the fact that it is constructed of very thin flexible material the 40 closure 16 can be drawn down into position where the adjusting collar 15 will engage the collar 9 as above described, thus properly seating the ring 9 and holding the screen 8 in position on the shoulder 7.

45 From the above description it will be seen that I have devised a simple and effective gasoline filter which in addition to filtering the impurities out of the gasoline will provide means for permitting the gasoline line to reach the outlet end under emergency conditions should the chamois become blocked.

What I claim as my invention is:

50 1. In gasoline filters, the combination with a casing having a gasoline inlet in one end and a gasoline outlet in the other, of a filtering unit mounted in the casing comprising spaced apart filtering media, one of which is impervious to water, and a by-pass for allowing the gasoline to reach the outlet without passing through the filtering medium impervious to water, upon such gasoline reaching a predetermined level in the casing.

55 2. In gasoline filters, the combination with a casing having a gasoline inlet in one end

and a gasoline outlet in the other, of a filtering unit mounted in the casing comprising spaced apart filtering media, one of which is impervious to water, and a screened by-pass for allowing the gasoline to reach the outlet without passing through the filtering medium impervious to water, upon such gasoline reaching a predetermined level in the casing. 70

3. In gasoline filters, the combination with a casing having a gasoline inlet, one end of said casing being open, of a closure for the open end having a suitable gasoline outlet, a removable filtering unit mounted in the casing comprising spaced apart filtering media, one of which is impervious to water, and means for permitting the gasoline to pass to the outlet side of the filtering medium impervious to water without passing therethrough, upon the height of the gasoline 85 in the casing reaching a predetermined level.

4. In gasoline filters, the combination with a casing having a gasoline inlet, one end of said casing being open, of a closure for the open end having a suitable gasoline outlet, a removable filtering unit mounted in the casing comprising spaced apart filtering media, one of which is impervious to water, and screened means for permitting the gasoline to pass to the outlet side of the filtering medium impervious to water without passing therethrough, upon the height of the gasoline 95 in the casing reaching a predetermined level.

5. In gasoline filters, the combination with a casing having a gasoline inlet in one end and a gasoline outlet in the other end, of a filtering screen partition extending across the casing, a suitably spaced apart chamois diaphragm mounted in the casing on the outlet side of the screen partition, and means between the screen and the chamois for permitting the gasoline after passing through the screen to flow to the outlet without passing through the chamois, upon the gasoline 105 reaching a predetermined level in the casing. 110

6. In gasoline filters, the combination with a casing having a gasoline inlet in one end and a gasoline outlet in the other end, of a filtering screen partition extending across the casing, a chamois carrying ring having an aperture in its top and removably held in engagement with the screen on the outlet side thereof, a chamois mounted on the outlet end of the ring, said chamois being of less diameter than the casing. 115

7. In gasoline filters, the combination with an internally shouldered casing having a gasoline inlet in one end and a gasoline outlet in the other end, of a filtering screen partition extending across the casing and seated on the shoulder, a ring having an outwardly extending flange on its inlet end and engaging the screen, a filtering medium 120

on the outlet end of the ring, a ring seating collar having an orifice through the outer end thereof, and means for holding the ring seating collar in engagement with the outer 5 face of the aforesaid flange.

8. In gasoline filters, the combination with an internally shouldered casing having a gasoline inlet in one end and a gasoline outlet in the other end, said casing having an 10 open peripheral flanged end outwardly inclined from top to bottom from the vertical and the plane of said shoulder inclined parallel to the said flange, of a filtering screen partition extending across the casing and 15 seated on the shoulder, a ring having an outwardly extending flange on its inlet end engaging the screen, a filtering medium on the outlet end of the ring, a ring seating collar having an orifice through the outer end
- thereof, and a closure for the opening end 20 of the casing having a gasoline outlet therein, said closure upon being mounted in position on the casing pressing the ring seating collar into engagement with the outwardly extending flange on the ring. 25
9. In gasoline filters, the combination with a casing having a gasoline inlet in one end and a gasoline outlet in the other end, of a filtering screen partition extending across the casing, a chamois carrying ring having 30 an aperture in its top and removably held in engagement with the screen on the outlet side thereof, a chamois mounted on the outlet end of the ring, said chamois being of less diameter than the casing, and means for 35 preventing the ring turning relatively to the casing.

HUGH ALLEN DEEKS.
